(57) **CLAIM**

The ornamental design for the blood filter, as shown and described.

DESCRIPTION

FIG. 1 is a front view of a first embodiment of a blood filter showing our new design;

FIG. 2 is a top view of the blood filter of FIG. 1;
FIG. 3 is a left side view of the blood filter of FIG. 1;
FIG. 4 is a right side view of the blood filter of FIG. 1;
FIG. 5 is a bottom view of the blood filter of FIG. 1;
FIG. 6 is a rear view of the blood filter of FIG. 1;
FIG. 7 is a front view of a second embodiment of a blood filter showing our new design;
FIG. 8 is a top view of the blood filter of FIG. 7;
FIG. 9 is a left side view of the blood filter of FIG. 7;
FIG. 10 is a right side view of the blood filter of FIG. 7;
FIG. 11 is a bottom view of the blood filter of FIG. 7;
FIG. 12 is a rear view of the blood filter of FIG. 7;
FIG. 13 is a front view of a third embodiment of a blood filter showing our new design;
FIG. 14 is a left side view of the blood filter of FIG. 13, the right side view being a mirror image;
FIG. 15 is a top view of the blood filter of FIG. 13, the bottom view being a mirror image;
FIG. 16 is a rear view of the blood filter of FIG. 13;
FIG. 17 is a front view of a fourth embodiment of a blood filter showing our new design;
FIG. 18 is a left side view of the blood filter of FIG. 17, the right side view being a mirror image;
FIG. 19 is a top view of the blood filter of FIG. 17, the bottom view being a mirror image;
FIG. 20 is a rear view of the blood filter of FIG. 17;
FIG. 21 is a front view of a fifth embodiment of a blood filter showing our new design;
FIG. 22 is a left side view of the blood filter of FIG. 21, the right side view being a mirror image;
FIG. 23 is a top view of the blood filter of FIG. 21; the bottom view being a mirror image;
FIG. 24 is a rear view of the blood filter of FIG. 21;
FIG. 25 is a front view of a sixth embodiment of a blood filter showing our new design;
FIG. 26 is a left side view of the blood filter of FIG. 25, the right side view being a mirror image;
FIG. 27 is a top view of the blood filter of FIG. 25; the bottom view being a mirror image; and,
FIG. 28 is a rear view of the blood filter of FIG. 25.
In the drawings, the broken are for the purpose of illustrating environment only and form no part of the claimed design.

1 Claim, 6 Drawing Sheets
